RAIL-LIFTING DEVICE

Kenneth Alderige, West Haven, Conn., assignor
to The Alderige Corporation, New Haven,
Conn., a corporation of Connecticut

Application October 14, 1942, Serial No. 461,943

10 Claims. (Cl. 254—121)

This invention relates to a rail-lifting or pulling device, and more especially to a device particularly designed for raising rails of a trolley track, for example, which have been embedded in the pavement.

In recent years many trolley tracks have been abandoned, and it is desirable for several reasons to remove the rails from the pavement in which the tracks have been laid. This work has been attended with considerable expense of labor, in that it is usually done principally by hand, as the pavement is broken up beside the rail, the spikes which hold the rails to the ties below the pavement removed, and then the rail lifted from the ties. This has been a laborious operation, not only from the standpoint of time, but also from the standpoint of number of men necessary, and the consequent expense of the labor involved.

It is contemplated by the present invention to provide a machine for doing this work, the device being in the form of a trailer which may be pulled by a heavy-duty truck or tractor, which in the case of a dump truck chassis, for example, is usually provided with a fluid pump. I make use of this fluid pump in providing power for hydraulic jacks used upon my device, which jacks in turn furnish the power for raising the rails from the roadbed or pavement. I have found it particularly desirable to use a hydraulic jack for this operation, for since liquid is practically non-compressible there will be no tendency for the apparatus to "jump" or spring upwardly if the rail suddenly gives way during the raising operation, as is often the case when the pavement breaks. The tractor, as will be apparent from the description hereinafter, not only furnishes the power for the lifting jacks, but also serves to draw the machine forwardly from one position to another as the rail is progressively lifted, so that the elevating mechanism operated by the jacks will be advanced to operate on progressively advanced points along the rail.

The device comprises a main frame which is drawn along the roadway, this frame having mounted thereon an elevating frame operated by the hydraulic jacks, from which elevating frame or auxiliary frame is suspended a shoe designed to travel below the rail when the machine is advanced, and to effect the raising of the rail when the auxiliary frame is elevated.

One object of the present invention is to provide a rail-lifting device of relatively simple construction, which will serve to lift a rail from the pavement rapidly and efficiently without dis-

turbing the pavement except along the area closely adjacent to the rail itself.

A still further object of the invention is the provision of a rail-lifting device which will speedily raise a rail from the pavement and which can be drawn along the rail by the power of an ordinary truck, the device being so constructed that it will be supported above the roadway during its advancing movement.

A still further object of the invention is to provide a relatively simple and inexpensive device having a pair of frame members designed to be normally held above the pavement or roadway, but which during the lifting operation will be forced against the pavement on each side of the rail to hold the pavement in place during the lifting operation.

To these and other ends the invention consists in the novel features and combinations of parts to be hereinafter described and claimed.

In the accompanying drawings:

Fig. 1 is a side elevational view of a rail-lifting device embodying my invention;

Fig. 2 is a top plan view of the device;

Fig. 3 is a partial sectional view on line 3—3 of Fig. 2, with the elevating or auxiliary frame in raised position;

Fig. 4 is a sectional view of the forward portion of the device showing its connection with the truck by which it is operated;

Fig. 5 is an enlarged sectional view of the rear end of the device;

Fig. 6 is a rear elevational view of the device;

Fig. 7 is a sectional view on line 7—7 of Fig. 1; and

Fig. 8 is a detail view of the shoe suspended from the elevating or auxiliary frame.

To illustrate a preferred embodiment of my invention, I have shown a main frame comprising a pair of longitudinally extending beams or frame members 10 and 11, these members being tied together to prevent lateral separation by transverse members 12 and 13. These beams are shown as of I shape, and the lower flanges may be turned upwardly adjacent their forward ends, as shown at 14, to facilitate travel of the device over a roadway.

These beams are supported at their forward ends from the chassis of a truck or tractor designated diagrammatically at 15, and as shown in Fig. 4, having an axle 16 and rear wheels 17. Upon the chassis of the device is a pump 18 which may be operated from the motor, and employed to operate the hydraulic jacks used in the elevating mechanism, as will be herein-

after explained. To the axle 16 is secured a pin 19 upon which is pivoted a clevis 20 connected to a short inclined tongue or tractor hitching member 21, which extends rearwardly and is provided with a transversely extending horizontal portion 22, the ends of which are secured to springs 23.

The rear end of each of the springs 23 is pivoted at 24 to one of the longitudinal beams 10 or 11, and the beams are supported from the springs by means of short bolts or rods 25 secured to the beams and resting upon the upper surfaces of the springs. The rods 25 are held between the beams themselves and plates 26 secured to the edges of the upper and lower flanges of each beam. Plates 27 likewise support the outer ends of the pivot bolts 24 to which the rear ends of the springs are secured. Extending transversely from one side to the other of the truck frame is a rod 28 and a beam 29. Upon the rod 28 is supported a hanger 30 by means of a roller 31, whereby the hanger may travel along the rod transversely of the truck. To the hanger is secured a stirrup 32 having thereon rollers 33 traveling on the lower flange of the beam 29. Suspended from the stirrup 32 is a plate 35 having a slot 36 therein through which the tongue or hitch member 21 extends. It will be apparent that when the front end of the hitch member 21 pivots about the bolt 19, the rear end of this member may move transversely of the truck and be guided in its movements by the connection of the hanger 30 and stirrup 32 to the rod 28 and beam 29. This connection will be useful whenever the device is not traveling in a straight line.

As has been explained, the forward end of the device is supported upon the springs 23, and will normally be held a short distance above the pavement to provide for easy forward travel. Likewise, as shown in Figs. 1 to 3, and Fig. 5, the rear end of the device will also be spring supported above the pavement. To this end a rear truck is provided consisting of wheels 37 and an axle 38. To this axle are secured a pair of forwardly extending and downwardly inclined members 39, each of which is pivoted to a bolt 40 secured to one of the longitudinally extending beams 10 or 11. These bolts are held between the web of the beams themselves and plates 41 secured to the outer edges of the upper and lower flanges of the beams.

Likewise pivoted to each of the bolts 40 is the forward end of a spring 42, the rear end of which is pivotally supported by the axle 38 by means of the spring shackle 43 and plate 44 secured to the axle. It will be understood that there will be one of these springs upon each of the beams 10 and 11, and that likewise each of these beams is provided with a bolt 45 which rests on the upper surface of the corresponding spring and serves to hold the rear end of the beam above the level of the pavement, as shown, for example, in Fig. 5. It will be seen, therefore, that the forward and rear ends of the devices are spring supported above the pavement, but that, upon sufficient pressure or weight being applied to the frame, the resistance of the springs will be sufficiently overcome to permit the lower flanges of the beams 10 and 11 to rest upon the pavement. This occurs during a rail-lifting operation, as shown in Fig. 3. It may also be stated that each of the bolts 45 is supported by the web portion of one of the beams at one

end, and at the other end by a plate 46 secured at the outer face of the beam.

Pivoted to the rod 13 is an elevating or auxiliary frame comprising a pair of beams 48 and 49, which, as shown in Fig. 2, lie above the beams 10 and 11, respectively. The front ends of these members are held in spaced relation by transverse rods 50 so that the two members form a rigid structure. Pivoted to the front end of each of the beams 48 and 49 is the piston 51 of a hydraulic jack 52, the lower end of which is pivoted at 53 on the lower flange of the corresponding beam 10 or 11, it being understood that there is one of these jacks for each of the elevating beams 48 and 49. In order to permit the bodies of the jacks 52 to rest upon the lower flanges of the beams 10 and 11, the webs of the latter are cut away, as shown at 53a, and across the opening thus made is secured a plate 54 so that the beams will withstand a longitudinal pull without danger of breaking. The upper and lower ends of the jacks 52 are suitably connected by the tubes 55 and 56 to the pump 18, whereby fluid under pressure may be introduced below the piston to raise the latter and elevate the auxiliary frame. The introduction of fluid to the jacks is controlled by a valve 57.

A pair of beams 58 and 59 are secured transversely across and at the lower edges of the beams 48 and 49 by means of plates 60 and tie rods 61. Welded to the upper surface of these beams are a pair of rods 62, as shown more particularly in Fig. 7, upon which rods is supported a plate 63. A threaded member 64 passes through this plate and is secured in place by means of the nut 65 above the plate. The lower end of this threaded member is provided with an eye 66 to which is secured a link 67 carrying a hook 68 from which is suspended a shoe 69. As shown in Fig. 8, to each side of this shoe is secured a link 70 to which are connected straps 71, the straps being in turn connected by links 72 to the hook 68.

It will be seen, therefore, that this shoe is suspended from the beams 48 and 49, and will be raised and lowered with these beams by the hydraulic jacks 52. This shoe is desired as shown in Figs. 1 and 3, for example, to be disposed below the base of the rail which is being lifted, and when the elevating frame is raised from the position shown in Fig. 1 to that shown in Fig. 3, the rail, which is designated by the numeral 73, will likewise be raised. The shoe 69 is rounded or sharpened at its front edge, as shown at 74, to render the front edge less blunt. The links 70 are connected with the tractor by means of chains 75, so that the shoe will be positively drawn forward as the tractor advances, and not rely upon its connection with the frame for its forward movement.

At the rear end of the main frame of the device there may be provided a second truck consisting of a frame 78 supported by a pair of ground wheels 79, as shown in Figs. 5 and 6, the frame 78 being secured to the axle 38. This frame may carry a roller 80 upon which the free or raised end of the rail 73 is supported when the device is in operation.

When it is desired to place my device in operation, the pavement is removed from a rail to a sufficient extent to permit the shoe 69 being placed underneath the rail. Liquid pressure is then introduced into the cylinders of the jacks 52 to raise the auxiliary frame, thus raising the end of the rail under which the shoe is disposed. When the

Jacks have been raised to a desired extent, or to their full extent, as shown in Fig. 3, the valve 51 is set to permit the lowering of the pistons 51 under the weight of the auxiliary frame, so that the weight of the rail will be removed, or substantially removed, from the shoe 69. At this time the entire trailer device is drawn forward by means of the truck 15 as far as possible, which will usually be as far as the rail has been loosened from the roadbed or ties 82 upon which it is supported. Parts of the device will now be in the position shown in Fig. 1, which may be considered the beginning of a rail-lifting operation. Hydraulic power is then admitted again to the jacks to raise the beams 48 and 49, which will effect a raising of the rail 73, as shown in Fig. 3, the rear end of the rail at this time being supported upon the roller 80. The elevating frame is then again lowered and the device drawn forward by means of the tractor 15 to bring the shoe below an advanced point in the rail for another lifting operation.

It will be apparent that as soon as a sufficient length of the rail has been raised, the free end of the latter will be supported upon the roller 80, as shown in Fig. 5, thus taking the weight of the rail and any downward pull thereon from the axle 38 and the main frame. It will also be understood that when the jacks 52 are exerting a lifting power upon the rail, as shown in Fig. 3, the pressure upon the beams 10 and 11 will overcome the springs at the front and rear of the device to a sufficient extent to permit the beams 10 and 11 to settle upon the roadway, where they will lie upon each side of the rail 73, as shown in Fig. 2, and thus during a lifting operation the bottom flanges of these beams hold the pavement in place while the rail is being pulled therefrom, so as to bring about a clean break between the pavement which is pulled up with the rail and that which remains in place. The spacing of the beams 10 and 11 may, of course, be regulated as desired, depending upon the type of pavement surrounding the rails. When, however, the auxiliary or elevating frame is lowered, as shown in Figs. 1 and 4, the beams 10 and 11 will be relieved of this pressure and the springs will be sufficient to overcome the weight of the device and hold it spaced above the pavement, so that, upon a forward movement, it will be carried at its rear end upon the wheels 37 and at its front end by the rear portion of the tractor 15. By thus raising the frame of the device out of contact with the roadway during its forward movement, the amount of tractive effort required is greatly reduced, and the device may be readily moved forwardly.

As shown in Fig. 4, the connection of the forward end of the device with the tractor is such that, while the member 21 may swing pivotally, as when the device is making a turn, lateral movement of the rear end of the member 21 will be controlled by the member 35 sliding transversely with respect to the tractor frame, as has been explained above.

It will also be understood that the connection of the shoe 69 with the elevating frame may be adjusted by moving the beams 58 and 59 after the bolts 61 have been removed or loosened so as to get any desired leverage needed to perform the lifting operation. The leverage which is required or which is expedient to use may vary considerably depending upon the type of pavement in which the rails have been laid.

It will be obvious that if the trailer device is employed with a truck not equipped with a pump,

such a pump and a gasoline engine to operate it may be mounted upon the beams 10 and 11 and connected with the jacks to operate the latter.

While I have shown and described a preferred embodiment of my invention, it will be understood that it is not to be limited to all of the details shown, but is capable of modification and variation within the spirit of the invention and within the scope of the claims.

10. What I claim is:

1. A device for raising rails from pavement or the like, said device having a main frame comprising a pair of spaced longitudinally extending beams disposed one on each side of a rail, an elevating frame mounted on said beams, means connecting said elevating frame to the rail including a shoe suspended from said elevating frame and disposed below the rail, means for raising said last-named frame to raise the shoe, and means connected to said main frame for drawing it forwardly, said means also being connected independently to said shoe to advance the latter.

2. A device for raising rails from pavement or the like, comprising a trailer frame having supporting wheels at one end thereof, means for supporting said frame from said wheels to permit lowering of the frame against the pavement, a tractor hitching member at the front end of said frame, said frame comprising a pair of spaced longitudinally extending members adapted to straddle a rail and bear on the pavement on each side thereof, springs supporting the front end of the frame from the tractor hitching member, an auxiliary frame pivoted adjacent one end to said trailer frame, means for connecting said auxiliary frame to the rail, means for raising the other end of said auxiliary frame to raise the rail, a tractor, and means supporting said hitching member from the rear portion of the tractor.

3. A device for raising rails from pavement or the like, comprising a trailer frame having supporting wheels at one end thereof, means for supporting said frame from said wheels to permit lowering of the frame against the pavement, a tractor hitching member at the front end of said frame, said frame comprising a pair of spaced longitudinally extending members adapted to straddle a rail and bear on the pavement on each side thereof, springs supporting the front end of the frame from the tractor hitching member, an auxiliary frame pivoted adjacent one end to said main frame, means for connecting said auxiliary frame to the rail, means for raising the other end of said auxiliary frame to raise the rail, said connecting means comprising a shoe suspended from the auxiliary frame and disposed beneath the rail, and draft means connected to said shoe by which it may be drawn forwardly beneath the rail.

4. A device for raising rails from pavement or the like, comprising a trailer frame having supporting wheels at the rear end thereof, spring means for supporting said frame from said wheels to permit lowering of the frame against the pavement, a tractor hitching member at the front end of said frame, said frame comprising a pair of spaced longitudinally extending members adapted to straddle a rail and bear on the pavement on each side thereof, springs supporting the front end of the frame from the tractor hitching member, an auxiliary frame pivoted adjacent one end to said main frame, means for connecting said auxiliary frame to the rail, and means for raising the other end of said auxiliary

frame to raise the rail, and said springs at the front and rear ends holding said frame members above the pavement when no power is applied to said auxiliary frame but permitting said members to contact the pavement during a rail-raising operation.

5. A device for raising rails from pavement or the like, comprising a trailer frame having supporting wheels at the rear end thereof, means for supporting said frame from said wheels to permit lowering of the frame against the pavement, a tractor hitching member at the front end of said frame, said frame comprising a pair of spaced longitudinally extending members adapted to straddle a rail and bear on the pavement on each side thereof, springs supporting the front end of the frame from the tractor hitching member, an auxiliary frame pivoted adjacent one end to said main frame, means for connecting said auxiliary frame to the rail, means for raising the other end of said auxiliary frame to raise the rail, a tractor, and means connecting said hitch to the tractor for movement laterally of the direction of travel.

6. A device for raising rails from pavement or the like, comprising a trailer frame having supporting wheels at one end thereof, means for supporting said frame from said wheels to permit lowering of the frame against the pavement, a tractor hitching member at the front end of said frame, said frame comprising a pair of spaced longitudinally extending members adapted to straddle a rail and bear on the pavement on each side thereof, springs supporting the front end of the frame from the tractor hitching member, an auxiliary frame pivoted adjacent one end to said main frame for movement in a vertical direction, a shoe suspended from said auxiliary frame and adapted for disposal beneath the rail, means for raising and lowering said auxiliary frame to raise the shoe, a draft device connected to said shoe, and a tractor connected to said hitching member and draft device.

7. A device for raising rails from pavement or the like, comprising a trailer frame having supporting wheels at one end thereof, means for supporting said frame from said wheels to permit lowering of the frame against the pavement, a tractor hitching member at the front end of said frame, said frame comprising a pair of spaced longitudinally extending members adapted to straddle a rail and bear on the pavement on each side thereof, springs supporting the front end of the frame from the tractor hitching member, an auxiliary frame pivoted adjacent one end to said main frame for raising and lowering movements, a shoe suspended from said auxiliary frame and adapted for disposal beneath the rail, means for raising and lowering said auxiliary

frame to raise the shoe, a draft device connected to said shoe, a tractor connected to said hitching member and draft device, said raising and lowering means comprising a hydraulic jack below the free end of said auxiliary frame, and a pressure source on the tractor connected to said jack.

8. In a device of the class described, a tractor, a trailer mechanism connected to the tractor and supported thereby at its forward end, a wheel support at the rear end of said mechanism, springs supporting the ends of said mechanism from the tractor and wheel support respectively, said mechanism comprising a pair of spaced longitudinal beams adapted to bear on the pavement on each side of a rail, an element supported on said beams for raising and lowering movement, a shoe suspended from said element and adapted for disposal beneath the rail, means for elevating said element to raise the shoe, and a draft device connecting said shoe to the tractor to advance the shoe and trailer when the tractor advances.

9. A device for raising rails from pavement or the like, said device having a main frame comprising a pair of spaced longitudinally extending beams disposed one on each side of a rail, an auxiliary frame pivoted to the main frame, means for raising the free end of the auxiliary frame, a shoe suspended from said auxiliary frame between the pivot and said end and adapted to be disposed below the rail, means for adjusting the point of suspension of said shoe with respect to the pivot of said auxiliary frame, supporting means at the front and rear ends of said frame and spring means supporting said beams from said supporting means to permit the beams to contact the pavement during a rail-raising operation.

10. A device for raising rails from pavement or the like, comprising a trailer frame having supporting wheels at the rear end thereof, means for supporting said frame from said wheels to permit lowering of the frame against the pavement, a tractor hitching member at the front end of said frame, said frame comprising a pair of spaced longitudinally extending members adapted to straddle a rail and bear on the pavement on each side thereof, springs supporting the front end of the frame from the tractor hitching member, an auxiliary frame pivoted adjacent one end to said main frame, means for connecting said auxiliary frame to the rail, means for raising the other end of said auxiliary frame to raise the rail, a second wheel support at the rear end of said trailer frame, and means on said last-named support upon which the rail is adapted to rest as the device progresses.

KENNETH ALDERIGE.
